MOTOR VEHICLE SPEED ALARM

Oscar Stankey, East St. Louis, Ill.

Application March 23, 1938, Serial No. 197,538

2 Claims. (Cl. 116—74)

This invention relates to alarms, and principally to an alarm that is to be cooperatively mounted on a motor vehicle so as to warn the occupants of the same at a predetermined speed of the vehicle, and has among its objects the production of such a device that will be simple, sturdy, safe, and which will be otherwise satisfactory and efficient for use wherever found applicable.

One of the principal objects of this invention is to so construct the alarm that it will be controlled by the pressure of the lubricating oil being circulated by the action of the oil pump of the vehicle during the operation of the latter.

Another object of the invention is to provide an alarm of the kind described that will be actuated only when the vehicle is being normally driven, and not while simply racing the engine or during some other driving relationship of the motor that would not reflect the true travelling speed of the vehicle.

A further object of my invention is to provide in an alarm of the kind described, a relief means whereby the danger of damage to the parts is obviated.

An added object of my invention is to so construct the alarm mechanism that the same may be adjusted so as to signal at a predeterminedly selective speed, or may be temporarily disconnected if so desired.

Many other objects and advantages of the construction herein shown and described will be obvious to those skilled in the art to which this invention appertains, as will be apparent from the disclosures herein given.

To this end, my invention consists in the novel arrangement, construction and combination of parts herein shown and described, and the uses mentioned, as will be more clearly pointed out in the claims hereunto appended.

In the drawing, wherein like reference characters indicate like or corresponding parts throughout the views,

Figure 1 is substantially a vertical cross-sectional view through a part of the device;

Figure 2 is a fragmentary top plan view of the same; and

Figure 3 is a perspective view of the gear-shift lever controlled parts of the device, connected to the valve shown in Fig. 1.

Referring more particularly to the drawing, wherein I have illustrated a preferred embodiment of my invention, there is shown a fragment of a motor vehicle of any desired or suitable size, shape and construction, the same not forming a part of my invention, and having the usual oil

pump 1 for conducting the lubricating medium forcibly to the various points of the vehicle desired, there being a conduit 2 communicating directly with the pressure side of said pump and leading to and communicating at its other end with the signal-actuating means as will be more clearly hereinafter described.

In motor vehicles, the pressure exerted by the oil pump varies approximately as the speed of the vehicle varies, and whereby effective lubrication is maintained during all driving speeds of the vehicle. Regardless of whether the oil pump is of the high-pressure type or of low pressure type, its pressure is always proportionate to the speed of engine operation, although not necessarily of the vehicle speed under certain conditions. However, when the car is being driven in its normal driving relationship, that is, in its "high gear," the oil pressure is approximately proportionate to the speed of the vehicle. At least it is sufficiently close enough thereto to suit the purposes of this invention.

In many instances the driver, as well as the other occupants of the vehicle do not realize that they are travelling at high speed, and therefore I have so constructed this alarm that it will be sounded or otherwise actuated automatically, whenever the speed of the vehicle passes beyond a predetermined limit.

Mounted at any convenient part of the vehicle, either in sight or out of sight, as desired, is the alarm device, the same being preferably mounted to a supporting base or plate 3. To this plate is affixed a valve chamber 4 having its inlet port 5 communicating with the conduit 2, and having an outlet port 8 for the discharge of the oil through the chamber.

A suitable valve 6 is slidably mounted within said chamber, the same being normally retained at one end of said chamber by a suitable spring 7 pressing the valve in said normal position for closing the inlet port 5. This valve may be in the form shown, if so desired, and in which instance it consists of a pair of axially spaced annular sections bearing snugly against the interior chamber wall, there being sufficient space between the pair of sections to permit the port 5 to discharge therebetween.

A valve stem 9 carries said pair of elements of the valve, and projects to one side through the end of the valve chamber for engagement by a control means actuated by the gear shift lever, in a manner to be more clearly hereinafter set forth. A duct 10 is provided into the valve stem from its innermost end and which opens

into the chamber just past and outwardly beyond the outermost of the pair of valve sections through a port 10', so that when the valve is in its position as shown in full lines in the drawing, 5 the conduit 2 communicates with the space between the valve sections, but as this is a closed space, it does not discharge therefrom nor actuate said valve. A shoulder or abutment 11 is provided in the chamber wall as a limit stop for 10 engagement with the valve in this position, said spring 7 tending to yieldably maintain said valve in position against said abutment 11, to shut off the conduit 2 from discharging through the outlet port 8 of the chamber, and retrieving the said 15 valve to said cut-off position as soon as the force keeping the valve in open position is released, as will be more apparent from the disclosures hereinafter given.

However, when the valve is shifted (to the dotted line position in the drawing) to move the valve just past the port 5, compressing the spring 7, the conduit 2 will then discharge into the valve chamber, passing therefrom into and through the duct 10 of the valve stem and emptying from 25 the chamber through the outlet port 8.

A diaphragm disk 12 is mounted to communicate with an be responsive to the pressure of the oil discharged through the port 8, said diaphragm being preferably within a housing having one 30 chamber 13 in open communication with said port 8 through a conduit 14, and another chamber 15 to the opposite side of said diaphragm and preferably forming a bearing for a plunger rod 16 fixed at one end to said diaphragm so as to be substantially unitary therewith and be actuated therethrough, the other end of said rod carrying a trip 17-18 to operate the alarm sounder.

Another bearing or support 19 may be carried 40 by the plate 3, and through which said plunger rod passes, and if so desired, said bearing 19 may act as an abutment stop to limit the retrieving movement of the plunger, by engagement with a transversely extending projection 20 carried by 45 said plunger.

A clapper bar 21 is mounted so as to be actuated by the movement of the plunger rod 16, as for example, intermediate its ends on the post 22 rotatably mounted on the plate 3, one end of 50 the bar carrying a striker 23 for sounding the bell 24 so as to sound the alarm or signal, and the other end of said bar having a cam element 25 thereon for operative engagement by said trip 17-18. The cam element has a cam face 26 in 55 the path of travel of the trip elements, and whereby the bar 21 is pivotally moved through the latter so as to move said striker away from said bell, said element having a sharp shoulder 27 at the end limit of the cam face 26, this shoulder being recessed so that as soon as the trip elements 17-18 pass the same, a spring 28 between 60 the post 22 and the plate 3 will immediately retrieve said bar toward its original position, causing the latter to strike against the bell and sound 65 the same. An abutment or projection 29 may be suitably interposed in the path of movement of the clapper bar 21, as for example intermediate the pivot post 22 and the striker, so as to normally keep the striker slightly from the bell, but 70 permit the same to more effectively strike the latter upon actuation of the clapper bar.

The part 17 of the trip is fixed rigidly on the plunger, but of such a size and shape that it does not engage the cam element during longitudinal movement of the plunger, while the other

part 18 is movably mounted with reference to the part 17. The part 18 is provided with a pair of ears 48-48 bent at an angle to the forward face of the element 18, and these ears are pivotally mounted on the part 17 so that when the parts 17 and 18 are substantially in parallel relation they are spaced apart slightly, and with the cam engaging edge of the part 18 moved into such a position that it clears the cam element. However, in the normal relationship of the trip parts, the part 18 is not arranged parallel to the part 17, but is pivoted or tilted relative thereto, so that the cam-engaging edge of the part 18 is in the path of the cam face, so as to engage the latter and actuate the clapper bar upon 15 travel forwardly of the plunger. A spring 30 may be interposed between the parts 17 and 18 to normally maintain the part 18 tilted and in position to engage with and actuate the clapper bar upon movement of the plunger. 20

A spring 31 is positioned about the plunger, one end of said spring being against the bearing 19 and the other end against a nut 32 adjustably mounted on a threaded sleeve encircling the plunger, one end of said sleeve abutting a collar 33 or other suitable element carried by the plunger, for the purpose.

When the plunger is operated, the operating force must be sufficient to overcome the pressure of the spring 31, the same being adjustable so 30 that the operating force may be increased or decreased, as desired, so as to set the device for different speeds, as will be explained shortly. As the plunger is thus operatively shifted, the pivotally mounted trip part 18 rides against the cam 35 face of the cam element, shifting the latter about its pivot post 22 against the force of the spring 28, until said part 18 moves past the shoulder 27, whereupon the spring 28 immediately retrieves the clapper bar and causes it to sound 40 the alarm. When the plunger is retracted, the part 18 strikes against said shoulder 27 and pivots said part 18 about its pivotal connection at its ears 48-48 about the fixed part 17, enabling the part 18 to lag behind the movement of the part 45 17 for a short distance, whereupon said part 18 then sharply snaps clear of the cam element to its normal position ready for again being in position to actuate the cam element of the clapper bar. 50

In order to prevent the sounding of the alarm unless the vehicle is being actually driven in high gear, I have provided a connection between the valve and the gear shift of the vehicle. For example, I have provided a crank having one arm 55: 34 rotatably journalled to any supporting structure, a second arm 35 extending at an angle thereto and carrying a collar 36 for operative engagement with the gear shift lever only when the latter is shifted into high gear. A spring 37 60: may be interposed between the crank and its support to yieldably hold the crank in position for engagement by the shift lever, and if desired there may be a stop 38 for limiting the pivotal movement of the crank into its shift lever engaging position. A slight notch or detent 39 may be provided in the collar 36 so as to hold the shift lever in firmer engagement therewith. A connecting link 40 may be interposed between 65: said crank and valve stem, being preferably detachable, so as to transmit movement therebetween and to throw them out of cooperating relationship when desired, as for example when about to idle the car or the like.

The crank is so mounted that when the gear 70: 75:

shift lever is in any other position except high gear, the valve stem will hold the valve in such position as to shut off the flow of the oil from operating the diaphragm. However, upon shifting the lever into high gear, said lever must engage said collar 36 of the crank, rocking the latter an amount sufficient to transmit this movement through the link to actuate the valve to open the inlet port into direct communication with the duct through the stem and in direct communication with the diaphragm, this shifting of the valve and its stem being yieldably resisted by the spring 7, of course.

Thus the pump is in direct communication with the signal control. Ordinarily, and while the vehicle is being driven in relatively low speeds, the pressure of the oil pump will not be sufficiently high to overcome the resistance of the adjustable spring 31, and the signal will not be sounded even though the shift lever is maintained in its high gear relationship.

The pump pressure is approximate to the speed of the motor, and under most normal conditions, to the speed of the vehicle, and hence as the vehicle speed rises, the pressure of the pumped oil rises proportionately. Therefore, as soon as this pressure is sufficient to operate the plunger, the signal will be sounded. While such a pressure, and corresponding speed is maintained or even exceeded, the plunger will be kept in its outermost position, but as soon as the speed of the vehicle drops, the oil pressure similarly drops, and the plunger will be retrieved to its retracted position. A subsequent sufficient increase in speed will again sound the signal, and a deceleration will again shift the signal operating means to normal position, and so on.

In order to avoid any damage to the device through the building up of an excess pressure within the various chambers and parts, and to relieve the pressure in the valve chamber so as to permit an efficient operation of the device, I have provided a relief by-pass. For this, a conduit 41 is arranged with one end communicating with the conduit 2 and with its other end communicating with the conduit 14 intermediate the valve chamber and the diaphragm. In the conduit 41 is arranged a suitable check valve 42, so that normally, the check valve will shut off passage through this duct during op-

eration of the device, but as soon as the pressure in the passage between the valve chamber and diaphragm exceeds that between the pump and the inlet port to the valve chamber, the check valve will be actuated through this differential of pressure and permit the oil in the duct 41 to escape back into the conduit 2.

If it is desired to disengage the device from control by the gear shift lever, a latch 43 may be provided to releasably latch the crank out of the path of the gear shift lever, and opening the port 5 into active pressure contact with the valve 6.

Having thus described my invention, it is obvious that various immaterial modifications may be made in the same without departing from the spirit of my invention; hence I do not wish to be understood as limiting myself to the exact form, arrangement, construction and combination of parts herein shown and described, or the uses mentioned.

What I claim as new and desire to secure by Letters Patent is:

1. In a motor vehicle having an oil pump and a gear shift lever, a signal; normally inoperative means adjustably interconnecting said signal and pump and controlled by the oil pump pressure to actuate said signal at substantially a predetermined speed of said vehicle; and means to set said last-mentioned means in operative position, engageable by said lever in high gear only whereby when said vehicle is being driven in high gear and upon reaching substantially a predetermined speed, the oil pressure of said pump will operate said signal.

2. In a motor vehicle having an oil pump and a movable speed shift element, a signal; means movably actuated by said oil and interconnecting said pump and signal to actuate the latter at substantially a predetermined oil pressure; and means to set said last-mentioned means in operative position and engageable by said shift element in high-speed position only, whereby when said vehicle is driven with said shift element in its high-speed position, the oil pressure will operate said first-mentioned means to actuate said signal at substantially a predetermined speed of the vehicle.

OSCAR STANKEY. 50
